UNITED STATES PATENT OFFICE.

JOHN R. SWANSON, OF ROCK ISLAND, ILLINOIS.

AUTOMATIC RETURN SYSTEM FOR BOILERS.

Application filed November 17, 1921. Serial No. 515,995.

To all whom it may concern:

Be it known that I, JOHN R. SWANSON, a citizen of the United States, residing at Rock Island, in the county of Rock Island 5 and State of Illinois, have invented certain new and useful Improvements in Automatic Return Systems for Boilers, of which the following is a specification.

My invention pertains to an automatic return system for boilers, by the operation of which water which has been converted into steam and expelled from the boiler, is returned thereto in a heated state after the steam has passed through the condensing 15 process. It is more specially adapted for use with a plant in connection with which a system of radiators is employed, but various other uses and adaptations thereof may be made.

One of the purposes of the invention is to do away with the present method of returning the water through a steam trap, controlled by means of a float, which arrangement is not satisfactory, on account 20 of the bearings being subject to leakage, and upon being tightened are liable to bind and not work properly.

Another purpose of the invention is to provide a mechanism in which the parts will 25 work freely, without friction, and in which a minimum amount of repairs is required.

Another object of the invention is to provide a mechanism which will work uninterruptedly, and without attention, under a 30 comparatively low degree of pressure, such as is usually contained in a steam heating system. As a result the water is maintained in the boiler at a uniform height, and there is a consequent saving in the use of fuel.

Another feature of the invention consists in connecting the same with the blow-out pipe of the boiler, tending to keep the same clear, and free from scale or other sediment.

While the invention is specially designed for use in connection with a steam condensing system, it can also be employed for introducing cold water into a boiler, in a substantially continuous manner, by substituting compressed air for the steam pressure.

The above mentioned, and other features and advantages of the invention will be more fully understood from the following specification, reference being had to the accompanying drawings, in which:

Fig. 1 is a front elevation of the tank system of the invention, with one of the tanks shown in vertical section.

Fig. 2 shows the steam chest 14 and ap- 60 purtenant mechanism.

Fig. 3 is a longitudinal section of the steam chest.

Fig. 4 is a cross-section on the broken line 4—4 of Fig. 3. 65

In Fig. 1 is shown a pair of enclosed tanks 1 and 2, connected at their upper ends by a bridge 3, such tanks being designed to be supported conveniently to a boiler, and a little above the water line therein. At its lower end the tank 1 is fitted with a pipe 4, connected with a pipe 5, which leads to the source of water supply. The pipe 5 is provided with a check-valve, as at 5^a, which prevents the return of the water 75 through such pipe. The tank 2 is similarly provided with a pipe 6, communicating with the water supply through a pipe 7, fitted with a check-valve at 7^a, preventing return of the water through the pipe 7. The pipes 4 and 6 are united by a pipe 8, from a central point of which connection is made through a pipe 9 with the boiler, below the water line thereof. Check-valves in the pipe 8 at 10 and 11 prevent movement of the 80 water from the pipe 8 into the pipes 4 or 6.

At their upper ends the tanks 1 and 2 are fitted with pipes 12 and 13, in communication with a steam-chest 14, mounted for 90 convenience at a point a little above the tanks. The body portion of the steam chest is supplied at all times with a charge of steam, under pressure, by means of a pipe 15, communicating with the boiler at a 95 point above the water line. From the steam-chest the tanks 1 and 2 are provided with alternate charges of steam, in the manner hereinafter described. In opposite ends of the steam-chest are piston heads 16 and 17, 100 united by a hollow rod 18, fitted at its ends with circular flanges 19, through which connection is made with the piston-heads, leaving spaces 20 in said heads.

The flanges 19 are provided with openings 19^a, permitting the passage of the steam into the spaces 20, and the pistons 16 and 17 are provided with central openings through which the steam can pass into the ends of the steam-chest. These openings are adapted to be alternately closed by means of valves 21 on the ends of a stem 22 slideable

in the rod 18. The valves are provided with extensions 23, projected outwardly in the openings in the piston heads, and provided with central openings 24, radiating from the 5 inner end of which are passages 25. When either valve 21 is at its inner position, as shown in the piston-head 16, the steam is permitted to pass through the openings 25 and 24 into the end of the steam-chest. This 10 has a tendency to force the piston-heads toward the other end of the cylinder, but this is prevented by a cushion of steam between the piston 17 and end of the steam-chest. This pressure can be relieved through a vent 15 26, at the outer end of which is a valve chamber 27, having an opening normally closed by a valve on the stem 28. Upon the valve being opened the pressure in the steam chest above the same is relieved, and the 20 piston travels toward that end of the cylinder. The projecting end of the part 23 comes in contact with the end of the cylinder, opening the valve 21 adjacent thereto, and closing the valve 21 at the opposite end 25 of the steam-chest.

The valves in the chambers 27 are alternately opened, by means hereinafter set forth, and are closed by means of springs 29 on the valve-stems 28. Mounted centrally of 30 the bridge 3 is a support 30, on which is rockingly supported an arm 31, provided at its ends with segments 32, to which are fixed cords 33, so as to operate on the faces thereof. Said cords pass downwardly through perforated plugs 34 and to the lower ends of 35 said cords are fixed weights 35, only one of which is shown. Extending upwardly from a central point of the arm 31 is a rod 36, having a pin and slot connection with an 40 arm 37, loosely mounted on a shaft 38, fixed to the side of the steam-chest. A disk 39 is also loosely supported on the shaft 38, and is provided on its outer face with pins 40 and 41, adapted for engagement with 45 notched arms 42, pivoted at their lower ends to brackets 43 supported from the sides of the steam-chest. Fixed in the periphery of the disk 39 is a weighted arm 44. The inner ends of the valve-rods 28 are connected with 50 the arms 42, above the pivotal points of such arms. As the arm 31 is rocked the arm 37 is swung in one direction or the other, such arm coming in contact with one of the pins 40 and 41, causing a partial rotation of the 55 disk. This raises the arm 44 until it passes a vertical point, whereupon the weight on such arm carries the same quickly downwardly, bringing the pin into engagement with the notch in one of the arms 42, and 60 moving such arm sufficiently to open the valve in the chamber 27 adjacent thereto.

Centrally of the steam-chest is an exhaust pipe 45, between the outlets of the pipes 12 and 13, and capable of alternate 65 communication with said pipes by means of

a slide-valve 46, movable with the rod 18, by means of flanges 47 on said rod. In the lower face of the valve 46 is a recess 48, of sufficient size to embrace the opening to the pipe 45 and that of one of the pipes 12 and 13 at a time.

The apparatus is shown in the drawings in a position in which the tank 2 will be assumed to be filled with water, which has been forced into the same under a moderate 75 pressure of approximately five pounds. The tank 1 being empty, the supporting quality of the water in the tank 2 has tended to raise the weight 35 therein, enabling the similar weight in the tank 1 to rock the arm 80 31 toward the left, causing a shifting of the steam-chest mechanism into the position shown in Fig. 3. This admits the steam through the pipe 13 to the tank 2, forcing the water downwardly out of the same, and 85 through the pipes 6, 8, and 9 to the boiler. At the same time the tank 1 is being filled with water through the pipes 4 and 5, and the steam or air in such tank escapes through the pipe 12 and exhaust pipe 45.

As the water raises in the tank 1 it carries the weight 35 upwardly, and, the weight in the tank 2 being no longer supported by the buoyancy of the water therein, the arm 31 is gradually rocked to move the arm 36 95 toward the right, until, when the tank 1 is filled with water, the disk 39 suddenly completes its movement, and the vent at the right-hand end of the steam-chest is opened, permitting a shifting of the piston in that 100 direction. This operation is kept up intermittently, at intervals of approximately one minute, several gallons of water being injected into the boiler at each operation of the tanks.

The pressure of the steam that enters the tanks 1 and 2 from above is intensely greater than that by means of which the water is forced into the tanks, as a result of which, when the steam is permitted to enter the 110 tanks, the water is quickly discharged therefrom. The discharge pipe 9 is preferably connected with the clean-out pipe of the boiler, as hereinbefore mentioned, the frequent passage of the successive charges of 115 water through such pipe into the boiler tending to keep the same free from sediment of any kind.

When a boiler is used in connection with a system of heat radiators the pressure of the steam is greatly reduced before entering the radiators, and it is this reduced pressure, exerted upon the water after condensation, that forces the same into the tanks. The water still retains its heat, so that as it is returned to the boiler there is no noticeable change in the temperature of the water therein.

As above stated, if it is desired to use the device with cold water, this can be done 120

by substituting a compressed air or other pressure for that of the condensing system.

The invention can also be adapted for use in connection with a water supply system, 5 by discharging from the tanks 1 and 2 into a common chamber, and controlling the outlet therefrom with float or other valves.

The tank mechanism is simple and efficient, and contains no bearings or other parts 10 which are liable to wear or injury. The cords 33 which support the weights are preferably formed of piano wire, which possesses recognized durable qualities.

What I claim and desire to secure by 15 Letters Patent, is:

1. In a device of the class described, a steam control mechanism, comprising a casing having an inlet and a pair of spaced outlets; a double-headed piston slidable in said 20 casing, provided in its ends with recesses communicating in one direction with the body of said casing and in the other direction with the ends thereof; valves in said recesses adapted to alternately open the 25 openings into the ends of said casing; means for alternately opening the outlets to said casing; valve-controlled outlets in the ends of said casings; and means on the outside of said casing for alternately opening said 30 last-named valve controlled outlets.

2. In a device of the class described, a steam control mechanism comprising a cylindrical casing having an inlet and a pair of spaced outlets; a pair of hollow piston heads 35 slidable in opposite ends of said casing, and united by a hollow rod, the space in said piston-heads communicating in one direction with the body of said casing, and in the other direction with the ends thereof; valves 40 in said piston-heads united by a stem slid- able in said rod, and provided with exten- sions adapted to engage the ends of said casing, to cause said valves to alternately open and close the openings between said

pistons and the ends of said casing; valve- 45 controlled vents in the ends of said casing, normally closed; means mounted on said casing for alternately opening and closing said vents; and means movable with said piston rod for alternately opening and clos- 50 ing said outlets.

3. In a device of the class described, a steam control mechanism embodying a cylindrical casing having an inlet and pair of spaced outlets; a pair of pistons slidable in 55 the ends of said casing, united by a hollow rod, said pistons having central recesses communicating in one direction with the body of said casing, and opening at their ends into the ends of said casing; a pair of valves in 60 said recesses united by a stem slidable in said rod, and adapted to alternately open and close the openings in the ends of said pistons; and extensions on said valves, hav- 65 ing passages furnishing a means of communication between said recesses and the end of the casing when the valves are in an open position, and closed when the valves are in a closed position, said extensions being capable of engagement with the ends of 70 said casing to cause a shifting of the positions of said valves.

4. In a device of the class described, a cylindrical casing having an inlet and pair of spaced outlets; a pair of hollow piston- 75 heads slidable in the ends of said casing, united by a hollow piston-rod, and in communica- tion with the body of the casing; and a pair of valves in said piston-heads united by a stem slidable in said piston-rod, 80 and provided with channels of communica- tion between the interior of said piston- heads and the ends of the casing, said chan- nels being alternately opened and closed by the movement of said valves. 85

In testimony whereof I affix my signature.

JOHN R. SWANSON.
